UNITED STATES PATENT OFFICE.

NORA H. MIMS, OF NEW YORK, N. Y.

DESIGN FOR A BAKING-PAN.

SPECIFICATION forming part of Design No. 24,407, dated June 18, 1895.

Application filed May 13, 1895. Serial No. 549,187. Term of patent 7 years.

To all whom it may concern:

Be it known that I, NORA H. MIMS, a citizen of the United States, residing in the city, county, and State of New York, have invented 5 a new Design for a Baking-Pan, of which the following is a specification.

The leading feature of this design for a baking pan consists in the shape and configuration of the rim that is circular with tapering 10 projections.

This design for a baking pan is represented in the drawing by a perspective view.

The pan A, is circular as shown and the rim 2, around the upper edge has projections 3, at equal intervals, and each projection has 15 edges that taper toward the outer ends.

I claim—

The design for a baking pan substantially as described and shown.

Signed by me this 9th day of May, 1895.

NORA H. MIMS.
